UNITED STATES PATENT OFFICE.

DOCTOR FRANKLIN OLIVER, OF OAKLAND, CALIFORNIA.

PENCIL.

1,253,711.

Specification of Letters Patent. Patented Jan. 15, 1918.

Application filed May 5, 1916. Serial No. 95,569.

To all whom it may concern:

Be it known that I, DOCTOR FRANKLIN OLIVER, a citizen of the United States, and a resident of Oakland, in the county of Alameda and State of California, have invented a new and Improved Pencil, of which the following is a full, clear, and exact description.

The invention relates to pencils having 10 movable leads, and its object is to provide a new and improved pencil arranged to securely hold the movable lead in projected position for writing or drawing purposes, and to allow convenient feeding of the lead 15 outwardly to project the lead terminal a desired distance beyond the point of the stock or barrel of the pencil.

In order to accomplish the desired result, use is made of a stock or barrel, a head 20 slideable forward and backward on the stock, and lead-engaging members held in the said stock and of which one is attached to the stock and the other is attached to the said head and moves with the same, the said 25 members having independent lead engaging means to normally hold the lead against return movement, the member attached to the head imparting a forward feeding movement to the lead on moving the head forward.

30 A practical embodiment of the invention is represented in the accompanying drawings forming a part of this specification, in which similar characters of reference indicate corresponding parts in all the views.

35 Figure 1 is a perspective view of the pencil;

Fig. 2 is an enlarged longitudinal central section of the same with the feeding and holding parts in normal position;

40 Fig. 3 is a similar view of the same with the feeding means in active position;

Fig. 4 is a perspective view of the head and the feeding member, parts of the latter being shown broken out; and

45 Fig. 5 is an enlarged cross section of the pencil on the line 5—5 of Fig. 2.

The stock or barrel 10, of wood, metal or other suitable material, is preferably pointed at its forward end 11 and the stock is provided with a central bore 12 extending throughout the length of the stock. On the rear or butt end of the stock 10 is mounted to slide forward and backward a head 13 provided with lengthwise extending slots 14 engaged by pins 15 held on the stock 10 to limit the forward and backward sliding

movement of the head 13 and to hold the latter against turning on the stock.

In the bore 12 is held loosely a tubular holding member 20 in which is mounted to 60 slide a tubular feeding member 21 containing the lead 22. The rear end of the feeding member 21 is attached to the top 23 of the head 13 so as to move with the latter, and the rear end of the holding member 20 is 65 provided with outwardly extending flanges 24 attached to the rear end of the stock 10 (see Fig. 5). A spring 25 is coiled around the rear end of the feeding member 21 and rests with its inner end on the flanges 24 and 70 abuts with its outer end against the under side of the top 23 of the head 13 to hold the latter normally in rearmost position, as plainly shown in Fig. 2. The forward end of the holding member 20 terminates a distance from the forward end of the stock 10, as plainly shown in Figs. 3 and 4, and the forward end of the feeding member 21 passes through a reduced portion 26 of the bore 12 and is adapted to project slightly beyond 80 the terminal of the stock 10 at the time the feeding member 21 is moved forward on the operator sliding the head 13 forward, as indicated in Fig. 3.

Both the holding member 20 and the feeding member 21 are split lengthwise and the side edges of the feeding member 21 are provided with inwardly extending flanges 30 provided at their inner edges with teeth 31 engaging the peripheral face of the lead 22, 90 as plainly shown in Figs. 2, 3 and 5. The side edges of the holding member 20 are provided with inwardly extending flanges 33 provided at their inner edges with ratchet teeth 34 engaging the peripheral face of the 95 lead 22 intermediate the ratchet teeth 31. By reference to Fig. 5 it will be noticed that the flanges 33 and their teeth 34 pass through the split in the feeding member 21 to engage the lead 22 as above described. The ratchet 100 teeth 31 and 34 extend rearwardly so that both sets of teeth grip the peripheral face of the lead 22 with sufficient force to prevent inward movement of the lead 22 at the same time holding the lead in such position for convenient writing or drawing purposes. When the head 13 is pushed forward by the user against the tension of the spring 25 then the feeding member 21 is moved in the same direction and 110 its ratchet teeth 31 now push the lead 22 forward a distance corresponding to the

movement given to the head 13. When the pressure is released on the head 13 the latter returns to its rearmost position by the action of the spring 25 thus pulling the feeding member 21 backward. During this return movement of the feeding member 21 its teeth readily glide over the peripheral face of the lead 22 held, however, against return movement by the teeth 34 of the holding member 20.

The top 23 of the head 13 is provided with a central opening 40 in register with the opening in the feeding member 21 to allow of filling the said feeding member with a lead 22 or pieces of lead from this end of the pencil.

The outer end of the head 13 is provided with an external screw thread 50 on which screws a cap 51 provided intermediate its ends with a partition 52 to be seated on the top 23 of the head 13 to normally close the opening 40. The outer end of the cap 51 is provided with an eraser 53 of rubber or other suitable material for erasing purposes.

The stock 10 is provided with a number of magazine recesses 60 extending from the rear end of the stock to about the beginning of the point 11, and the said recesses 60 are arranged in a circle concentric to the bore 12, as plainly indicated in Fig. 5. Each of the recesses 60 is adapted to contain an extra lead 61, and the top 23 of the cap 13 is provided with openings 62 in alinement with the recesses 60 to permit of placing the leads 61 into the said recesses 60 or removing the same therefrom at the time the cap 51 is removed from the head 13. Normally the partition 52 closes the openings 62.

The pencil shown and described is very simple and durable in construction, composed of comparatively few parts not liable easily to get out of order.

It will also be noticed that the lead 22 is gripped practically throughout the length thereof by the teeth 31 and 34 to securely hold the lead against inward movement but to allow outward feeding movement on the operator pressing the head 13, as previously explained.

Having thus described my invention, I claim as new and desire to secure by Letters Patent:—

1. A pencil, comprising a stock having a central bore, a head slidable on the butt end of the said stock, and telescoping tubular members extending within the said bore and both having gripping means independently engaging the lead held in the inner member, one of the members being secured to the stock and the other member being secured to the said head to move with the latter, the said gripping means normally holding the lead against return movement and allowing forward feeding thereof.

2. A pencil, comprising a stock having a central bore, a head slidable forward and backward on the said stock, a tubular feeding member in the said bore and attached to the said head to move with the latter, the said feeding member having gripping means engaging the lead held in the said feeding member to move the lead forward on imparting a forward sliding movement to the said head, and a second tubular member in the stock and in which the first tubular member slides, said second tubular member having gripping means for holding the lead against return movement during the return movement of the feeding member, the feed gripping means assisting the said holding means to hold the lead against return movement during the time the feeding member is in non-feeding inactive position.

3. A pencil, comprising a stock having a central bore, a spring-pressed head slidable forward and backward on the butt ends of the said stock, a tubular holding member within the said bore and attached to the said stock, the said holding member being split and having its edges terminating in inwardly extending flanges having ratchet teeth, a tubular feeding member slidable within the said holding member and adapted to contain a lead, the rear end of the said feeding member being attached to the said head, the said feeding member being split for the passage of the said flanges of the holding member, the edges of the said gripping member terminating in inwardly extending flanges having ratchet teeth, the ratchet teeth of both the said holding member and the said feeding member being adapted to engage the lead.

4. A pencil, comprising a stock having a central bore, a spring-pressed head slidable forward and backward on the butt end of the said stock, a tubular holding member within the said bore and attached to the said stock, the said holding member being split and having its edges terminating in inwardly extending flanges having ratchet teeth, a tubular feeding member slidable within the said holding member and adapted to contain a lead, the rear end of the said feeding member being attached to the said head, the said feeding member being split for the passage of the said flanges of the holding member, the edges of the said feeding member terminating in inwardly extending flanges having ratchet teeth, the ratchet teeth of both the said holding member and the said feeding member being adapted to engage the lead, and the said ratchet teeth of both members extending in the same direction to hold the lead against return movement.

5. A pencil, comprising a stock having a central bore, a spring-pressed head slidable forward and backward on the said butt end

of the said stock, a tubular holding member within the said bore and attached to the said stock, the said holding member being split and having its edges terminating in inwardly extending flanges having ratchet teeth, a tubular feeding member slidable within the said holding member and adapted to contain a lead, the rear end of the said feeding member being attached 10 to the said head, the said feeding member being split for the passage of the said flanges of the holding member, the edges of the said feeding member terminating in inwardly extending flanges having ratchet teeth, the ratchet teeth of both the said holding member and the said feeding member being adapted to engage the lead, the said holding member terminating a distance

from the forward end of the stock and the said feeding member extending a short distance beyond the forward end of the stock. 20

6. A pencil, comprising a stock having a central bore, a head slideable on the stock, a tubular feeding member in the stock and having its end secured to the said head, 25 said tubular member having means for feeding the lead held therein, a second tubular member in the stock and in which the first tubular member slides, said second tubular member being provided with means 30 for holding the lead against return movement, and a spring surrounding the feeding tubular member between the head and the end of the stock.

DOCTOR FRANKLIN OLIVER.
